UNITED STATES PATENT OFFICE.

FRANK T. COPE, OF SALEM, OHIO, ASSIGNOR TO THE ELECTRIC FURNACE COMPANY, OF SALEM, OHIO, A CORPORATION OF OHIO.

FURNACE-DOOR-HEATING MECHANISM.

Application filed March 5, 1925. Serial No. 13,134.

To all whom it may concern:

Be it known that I, FRANK T. COPE, a citizen of the United States, residing at Salem, in the county of Columbiana and 5 State of Ohio, have invented certain new and useful Improvements in Furnace-Door-Heating Mechanism, of which the following is a specification.

This invention relates to electrically 10 heated doors for electric furnaces and the objects of the invention are to provide means for mounting an electric resistor upon the inner surface of the door of an electric furnace, whereby the door may be opened 15 without interrupting the circuit to the resistors upon the furnace walls; a further object being to provide means whereby the circuit to the resistor upon the door is automatically broken when the door is opened, to prevent 20 overheating of the furnace plate at the end of the furnace adjacent to the door.

The above and other objects may be attained by constructing the mechanism in the manner illustrated in the accompanying 25 drawing, in which—

The figure is a vertical sectional view of the end portion of an electric furnace and door provided with heating means embodying the invention.

Similar numerals refer to similar parts 30 throughout the drawing.

One end portion of an electric furnace is shown at 1, provided with a door opening 2 adapted to be closed by the vertically sliding 35 door 3. Electric heating elements in the form of resistor grids are shown diagrammatically at 4 and 5 and adapted to be located upon opposite side walls of the furnace.

The line wires 6 and 7 are connected to 40 the ends of the grids 4 and 5 respectively. The other end of each grid is connected by a wire 8 to one of the contact bars 9, each of said bars being pivotally suspended upon a 45 link 10 supported upon the stationary frame 11 and arranged to be urged toward each other as by the springs 12.

A post 13 is rigidly mounted upon the 50 door and provided with a rigid arm 14 carrying an insulation plug 15 arranged to contact with and support the contact bars 9 when the door is in closed position, as shown in the drawing.

A contact plate 16 is fixed upon each side 55 of the tapered lower end of the plug and

arranged to engage the adjacent contact bar 9. A resistor grid 17 is mounted upon the inner face of the door, each terminal 18 thereof being connected as by a flexible wire 19 with one of the contact plates 16. 60

With the furnace door closed as shown in the drawing, the circuit will be completed from the line wires 6 through the grid 4 and adjacent wire 8, contact bar 9, contact plate 16 and wire 19 through the resistor 17 upon the door, then through the other wire 19, contact plate 16, contact bar 9 and wire 8, through the resistor grid 5 and line wire 7. 65

When it is necessary to open the door to charge or empty the furnace, the raising of 70 the door will move the plug 15 out of contact with the bars 9, the springs 12 moving said bars into contact with each other. No interruption of the circuit has occurred by this action as until the bars 9 were in contact, the circuit was being completed through the plates 16 and wires 19 to the door heating element. 75

As soon as the plug 15 is raised out of contact with the bars 9, the circuit to the 80 door heating element 17 is broken. Thus while the door is in the opened or raised position, the heating element thereon is out of circuit and overheating of the furnace plate 20 to an injurious extent is eliminated. 85

It will be obvious that as the door is closed, the plug 15 will again contact with the bars 9, supporting them and again completing the circuit through the heating element 17 upon the door. 90

With this construction, it will be seen that the door may be opened and closed in order to charge or withdraw material from the furnace without interrupting the circuit to the resistors within the furnace, and by providing the automatic switch, the circuit to the door resistor is automatically broken when the door is opened, preventing damage to the end plate of the furnace when the door is in the raised position, without cutting off 100 the current to the resistors upon the side walls of the furnace. 105

I claim:—

1. An electric furnace including a resistor within the furnace, a movable door upon the furnace, a resistor carried upon the door, an electric circuit in which said resistors are normally located and means whereby the circuit to the door resistor is broken as the door is opened and is closed 110

2
as the door is closed without interrupting the circuit to the resistor within the furnace.

2. An electric furnace including a resistor within the furnace, a movable door upon the furnace, a resistor carried upon the door, an electric circuit in which said resistors are normally located and means whereby the opening of the door breaks the circuit to the resistor upon the door without interrupting the circuit to the resistor within the furnace.

3. An electric furnace including a movable door, a resistor carried upon the door, a circuit for said resistor and means whereby the circuit is broken as the door is opened and whereby the circuit is closed as the door is closed.

4. An electric furnace including a resistor within the furnace, a movable door upon the furnace, a resistor carried upon the door, an electric circuit in which the resistors are normally located, and a switch in the cir-

cuit, operated by the movement of the door, to break the circuit to the resistor upon the door when the door is opened, without interrupting the circuit to the resistor within the furnace.

5. An electric furnace including a pair of resistors within the furnace, a movable door upon the furnace, a resistor carried upon the door, a contact plug carried by the door and provided with contact plates, flexible wires connecting said contact plates with the door resistor, a pair of spring pressed contacts connected to the furnace resistors and arranged to be separated by the plug and to be engaged by said contact plates when the door is closed, and means connecting the furnace resistors with a source of electric energy.

In testimony that I claim the above, I have hereunto subscribed my name.

FRANK T. COPE.
